UNITED STATES PATENT OFFICE.

JAMES M. COOK, OF TAUNTON, MASSACHUSETTS.

EXCLUDING DUST FROM RAILROAD-CARS.

Specification of Letters Patent No. 9,671, dated April 19, 1853.

To all whom it may concern:

Be it known that I, JAMES M. COOK, of Taunton, in the county of Bristol and State of Massachusetts, have invented a new and useful improvement, contrivance, or mode of preventing dust, sparks, or cinders from entering the windows of a carriage when in movement on a railway; and I do hereby declare that the same is fully described and represented in the following specification and the accompanying drawings, figures, letters, and references thereof.

Of the said drawings, Figure 1 denotes an elevation of a part of the side of a carriage to the window openings of which my improvement is represented as applied. Fig. 2, is a top view of one of my dust guards or deflectors. Fig. 3, is a side view of it. Fig. 4, is a cross section of it.

In the said drawings A, denotes the carriage body of which B, B, B, &c., are the window openings. To each of these openings, the dust guard or deflector seen at C, C, is applied. It is placed on the outside of a car, and made not only to extend vertically up against the side of the window, but horizontally underneath the window, the vertical part of it being seen at a, while the horizontal part of it is denoted at b. These two parts are rounded at their angle of junction and they are made to project about six inches from the side of the car.

In the drawings, the deflector is shown as composed of one strip of metal d united at its inner edge to another vertical piece e, whose outer edges f, g, stand at right angles to each other, and are made of equal length. The outer edge of the deflector is curved as seen at m, for the purpose of gathering in the air, or rolling it inward and toward the car under it—while the car is in movement in the direction denoted by the arrow D'.

Any convenient and proper method of securing the deflector to the window frame may be adopted. I usually insert small pins h h, in the upper edge of the window sill and cause them to project above the sill and into corresponding holes formed in the support part e, of the deflector. When these holes are properly made in both edges of the support piece, the deflector can readily be adapted to either side of the window. The upper part of the de-

flector may be secured in place by turned buttons i, or any other suitable contrivance. A simple board or flat plate placed vertically against the side of a window opening and made to stand at an angle of forty-five degrees, or thereabout to the side of a car, and to incline from the direction in which the car is to run, will not effectually prevent the entrance of dust or cinders into the car window, as there is much of the dust that rises upward from the track which cannot be excluded by such a contrivance.

By making the deflector to extend underneath the window as well as upward against its side, we not only greatly increase the deflecting power of it, but we create when the car is in movement plunging currents of air which sweeping downward have a wonderful effect to prevent the dust from entering the windows. My invention has been thoroughly tested in practice and has been found to effectually answer the purpose for which it was intended.

I lay no claim to the application of vertical blinds, shutters, or screens, on the outside of railroad cars and made to stand at angles of about forty-five degrees therewith, and for the purpose of preventing the entrance of dust, smoke or cinders into the windows thereof. But

What I do claim as my invention is—
My improvement in the manner of constructing and applying a deflector to the outside of a railway car, the same consisting not only in making it to extend along the bottom horizontal or lower part, but up along the vertical side of a window opening, substantially as described, and so that while the car is in motion, the air impinged against by the vertical face of the guard will be driven or moved downward and made to pass under or over the guard, so as to prevent the dust thrown directly upward from the track, as well as that moving horizontally or otherwise from entering the windows as described.

In testimony whereof I have hereto set my signature this twenty-ninth day of January, A. D. 1853.

JAS. M. COOK.
